CLAIM

The ornamental design for an F type coaxial compression connector, as shown and described.

DESCRIPTION

FIG. 1 is a side perspective view of an F type coaxial compression connector showing the front, top, and left of my new design;

FIG. 2 is a side perspective view thereof showing the rear, top and right of my new design;

FIG. 3 is a right side view thereof which is a mirror image of the left side view;

FIG. 4 is a top view thereof which is a mirror image of the bottom view;

FIG. 5 is a front view thereof; and,

FIG. 6 is a rear view thereof.

The broken line portions of the figure drawings are included to show unclaimed subject matter only and form no part of the claimed design.

1 Claim, 1 Drawing Sheet
